LINE DRIVE AND FEED FOR STOKERS

Hurshel H. Fitch, Auburn, Ind., assignor to
 Auburn Foundry, Inc., Auburn, Ind., a corporation

Application May 21, 1938, Serial No. 209,278

3 Claims. (Cl. 110—45)

This invention relates to a direct feeding device for supplying solid fuel from a bin to a furnace, boiler or the like.

This application discloses improvements upon the basic invention disclosed and claimed in the copending allowed application, Serial No. 90,090, filed July 11, 1936, and entitled, "Line drive and feed for stoker," which application was allowed November 26, 1937, and is now Patent No. 2,208,751 dated July 23, 1940, and such matter therein as was claimed and divided therefrom upon official requirement.

The chief object of the invention is to improve the construction, operation and assembly or fabrication of a device of the character illustrated and described in the copending application.

One feature of the invention is in the bin plate structure, whereby the fuel supply tube may be adjustably supported, the fuel in the bin may be rendered accessible for pulling down purposes or both may be accomplished.

Another object of the invention is to provide an improved fuel supply arrangement within the bin structure, associating the same with a floating type bearing for the fuel supplying screw or both may be employed.

Another feature of the invention consists in a combination outboard bearing provided for the air conduit and the worm enclosing conduit and which bearing furthermore is adapted to support one end of a clean-out tube and a clean-out closure for that tube.

Another feature of the invention consists in the interconnected thrust absorbing and power applying structure and the detachable association between the parts thereof.

Other objects and features will be pointed out more fully in the following description.

The full nature of the invention will be understood from the accompanying drawings and the following description and claims:

In the drawings

Fig. 1 is a top plan view of one embodiment of the invention from the retort to the air and power supplying end.

Fig. 2 is a longitudinal sectional view through the retort and the power supplying and thrust bearing mechanism associated therewith.

Fig. 3 is a similar view through the fuel supply portion, the retort and the bin including the bin plate structure.

Figs. 2 and 3 are longitudinal sections taken in the same plane and one is a continuation of the other.

Fig. 4 is a front view of a portion of the bin plate structure.

Fig. 5 is a transverse sectional view taken on line 5—5 of Fig. 1 and in the direction of the arrows.

Reference first will be had to Figs. 1 and 2. In said figures there is illustrated a main casting 10 having a curved channel 11 extending therethrough terminating in projecting collar portions 12 of tubular character. It also includes a central throat 13. A casting 14 superimposed thereabove includes the annular chamber 15 formed by the throat portion 16. Superposed thereabove is the tuyère construction 17 having the fuel receiving portion or hopper 18 and the air supplying openings 19, which communicate with the chamber 20 within the tuyère structure, in turn communicating as at 21 with the chamber 15 which in turn communicates as at 22 with the chamber 23. Chamber 23 is provided with two outlets in spaced relation. One outlet is provided with an air supply tube 24. Another outlet is provided with an inclined clean-out tube 25, the inclination permitting riddlings cleaning.

In spaced relation to the base portion 10, is the outboard bearing casting 28 connected thereto by any suitable means such as the portion 9. The outboard bearing casting 28 has an opening therethrough which at one end receives the downwardly inclined air supplying tube 24 and at the opposite side receives the air supply tube 30 which communicate through the casting opening. The air supply tube 30 is connected at the opposite end to a fan or blower structure 31 suitably associated with the power mechanism—see Fig. 1.

The opposite side of the outboard bearing 28 includes an opening, not shown, similar to the opening 29 and the same is adapted to receive and support the other end of the clean-out tube 25. The cleanout opening in the outboard bearing is closed by a closure member 32 which is retained in closed position by means of the thumb screw 33 bearing thereon, which thumb screw is threadedly supported as at 34 by an arm 35 having a curved hook portion 36, the free end 37 of which is adapted to engage a lug 38 on the side of the casting 28. The other end of the arm 35 has a relatively detachable hinge type association with a tubular extension 39 formed in a collar portion 40. Collar portion 40 rigidly supports the tube 41 that has one end seated in the enlarged bore 42 in the collar 12.

Mounted within the tube 41 is the screw 43, which herein is shown—see Fig. 2—as terminating in a socketed end 44 provided with aligned

apertures 45 that are countersunk as at 46 and which aligned apertures mount the pin 47. Pin 47 extends through the aligned apertures 48 in the adjacent end of a tube 49 nested in the recess 50 of the socketed end 44 of the worm 43.

In Figs. 1 and 2 there is illustrated a gear case 51 which encloses a gear reduction device driven by suitable motor means and the power arrangement includes a stub shaft 52 projecting therefrom and into the housing member 53 detachably secured to the gear casing by means of bolts not shown. The end of this shaft mounts a pin 54 that projects laterally from the shaft.

Housing 53 at its opposite end includes a bore 57 mounting a bushing 58 that rotatably supports a second shaft 59 that projects from the housing 53. The housing enclosed end of said shaft 59 is of socket type, as indicated at 60, and the socket is slotted as at 61 to receive the pin 54. The housing 53 has an abutment 62 and between 10 said abutment and the socket portion 60 is interposed an anti-friction structure 63. The housing structure 53 is suitably connected to the arm 64 which is a part of the motor base. A sleeve 66 is suitably secured to the flange 55 of the housing 53 by means of bolts, not shown. A set screw 68, supported by and extending through the sleeve 66 engages the sleeve enclosed end of the tube 41 and serves as a stop therefor. The projecting end of the shaft 59 is telescopically received by the right hand end of the driving tube or driven member 49.

The projecting end of the shaft 59 is apertured as at 69 to receive a bolt 70 mounted in the aligned apertures 71 of the tube 49. The bolt is suitably secured in that position, thus detachably connecting the shaft and tube together and by means of a nut 72. The resulting construction, therefore, is of detachable type and is also of the thrust bearing type. This permits the screw and/or the tube 41 to be detached and removed without disassociating all of the mechanism.

Reference will now be had to Figs. 3 and 4. In Fig. 3 there is illustrated a tube 73, the same being axially aligned with the tube 41 and the right hand end of the tube 73 is received by the enlarged bore portion 74 of the retort structure 10. A coupling sleeve 75 suitably associates the adjacent ends of the tubes 73 and 76. The tube 76 extends through an opening in the bin, said opening being closed by a bin plate structure 77. The latter has an opening 78 suitably closed by a closure plate 79 detachably secured as at 80 to the plate. The plate has an opening 81. A collar type bearing 82 is suitably secured as at 83 to the plate. It has a partially spherical surface 84.

Supporting the tube 76 in the opening 81 is a pair of complementary tube enveloping members 85 having an interlocking connection as at 86—see Fig. 3—and having tube bearing portions 87—see Fig. 4. Pivot screws 88 are threadedly mounted as at 89 in the enveloping portion 82 and engage in the aligned recesses 90 in the partially spherical exterior surface of the enveloping structure 85. Thus, the tube may be axially aligned

without regard to the direction of the bin wall 91 having the opening 92 therein closed by the bin plate 77. The tube 76 is extended within the bin and adjacent the opening 81 of the plate is suitably relieved as at 93, thus exposing the screw 43 which extends from a point to the right of the retort entirely through the retort and terminates in a free end 94. The flights on the worm preferably are of equal diameter. The shaft of the worm within the bin preferably is tapered as at 95, so that the worm increasingly draws more fuel as it approaches the bin wall adjacent the retort.

Within the bin and suitably secured, for example, to the bottom thereof, as at 96, is a bearing structure 97 that has the bearing portion 98 that supports the free but relieved end of the tube 76. Thus, the worm is exposed to the fuel which is drawn by it through the tubes 76 and 73 and is discharged upwardly through the neck 13, throat 16 into the hopper 18 for combustion purposes. The initial operation of the device fills the portion of the tube 41, and thereafter the fuel has only one outlet or possibility of escape and that is through the retort upwardly directed discharge.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a stoker structure, the combination with a retort device, an elongated tube supported at one end thereby and projecting therefrom, a worm therein, and an elongated air supply tube similarly supported by and projecting from the device, of a singular outboard bearing type support having one end carried by the device and having means remote from the device connecting to both tubes for supporting and maintaining same in spaced relation to each other remote from the device.

2. A structure as defined by claim 1, characterized by the addition of a clean-out tube connected at one end to the retort device and supported at the opposite end by the outboard support, a closure means for the clean-out means at said outboard end, and means detachably securing the closure means to the support.

3. A structure as defined by claim 1, characterized by the addition of a clean-out tube supported at opposite ends by the device and said remote means, and closure means normally closing the remote means supported end of the clean-out tube and movable to permit device cleaning through the clean-out tube, said remote means including a plate-like member with three tube receivable openings therethrough, the openings being in a common plane, the middle opening seating the worm tube.
